UNITED STATES PATENT OFFICE.

RICHARD P. BURKHARDT, OF DAYTON, OHIO.

CHAIR-SEAT.

SPECIFICATION forming part of Letters Patent No. 340,029, dated April 13, 1886.

Application filed February 1, 1886. Serial No. 190,397. (No model.)

To all whom it may concern:

Be it known that I, RICHARD P. BURKHARDT, a citizen of the United States, residing at Dayton, in the county of Montgomery and State of Ohio, have invented certain new and useful Improvements in Chair-Seats, of which the following is a full, clear, and exact description, reference being had to the accompanying drawings, forming a part of this specification.

My invention relates to that class of chair-seats known as "cushioned" seats, which are usually provided with springs covered by suitable upholstering.

The object of my invention is to cheapen and simplify the construction of this class of seats, and to dispense with the usual bottom support for the springs.

The novelty will be herein set forth, and specifically pointed out in the claim.

In the accompanying drawings, Figure 1 is a bottom plan view of my improved seat. Fig. 2 is a sectional side elevation of the same from front to back. Fig. 3 is a bottom plan view illustrating a modification in the construction. Fig. 4 is a diminished plan view representing a further modification.

The same letters of reference are used to indicate identical parts in all the figures.

A represents the usual or any ordinary seat-frame, secured between the side bars of which, close to the front and rear bars, respectively, are two, preferably round, wooden bars, B, whose ends, as shown, are mortised or recessed into the side bar. Upon these bars are secured the double coiled springs C, whose inner upwardly-projecting ends form loops, as shown, and whose lower ends pass under and engage with the front and rear bars of the seat-frame. If desired, these ends, instead of simply bearing against the under side of the seat-frame, may be inserted and secured therein to prevent accidental displacement and make a more secure fastening.

The number of springs on each of the bars

B is equal, and for an ordinary chair three for each bar will be found sufficient, though as many may be used as desired. The loops of the springs, which, as shown in Fig. 2, project up above the level of the seat-frame, are connected in opposite pairs by sheet-metal straps D, which, uniting the springs, form a support for the upholstering E, which covers the seat in the usual manner.

Instead of sheet-metal straps D, wire, rope, or twine F, as seen in Fig. 3, may be employed to unite the loops of the springs and form a support for the covering or upholstering, and, if desired, a cross-strap, G, as seen in Fig. 4, may be employed to connect and steady the straps D.

In this manner I provide an inexpensive spring or cushioned seat for chairs, possessing all the advantages of more expensive cushioned spring-seats, wherein a lower support for the springs is usually provided.

I am aware that it is not new to use double coiled springs for cushioned seats, nor is it new to connect such springs by interlaced straps, as shown in Letters Patent Nos. 78,705, 70 Reissue 3,664, 89,736, and 102,386, and I do not claim such constructions; but

Having thus fully described my invention, I claim—

The combination, with the seat-frame A, of the bars B on a level with the frame, and having their ends recessed in the frame, double coiled springs C, whose lower ends engage with the under side of the frame and are supported thereby, and whose upper ends project inwardly to form loops above the level of the top of the frame, the straps D, connecting the opposite pairs of said springs, and the covering E, the whole constructed and arranged substantially in the manner and for the purpose specified.

RICHARD P. BURKHARDT.
